UNITED STATES PATENT OFFICE.

NIEL MCFADDEN AND ALBERT E. STEWART, OF FRANKLIN, NEW HAMPSHIRE, ASSIGNEES TO ACME KNITTING MACHINE AND NEEDLE COMPANY, OF FRANKLIN, NEW HAMPSHIRE, A CORPORATION OF NEW HAMPSHIRE.

KNITTING-MACHINE.

1,083,690.

Specification of Letters Patent.

Patented Jan. 6, 1914.

Application filed April 20, 1911. Serial No. 622,365.

To all whom it may concern:

Be it known that we, NIEL MCFADDEN and ALBERT E. STEWART, both of Franklin, in the county of Merrimack and State of New Hampshire, have invented certain new and useful Improvements in Knitting Machines, of which the following is a specification, reference being had to the accompanying drawings, forming part thereof.

10 This invention has reference to improvements in rotary knitting and particularly to that class of rotary knitting machines having skeleton cylinders, so called, located between the needle cylinders and the cam cylinders.

One object of this invention is to improve knitting machines of this nature to facilitate the operation thereof on yarns of high numbers or on coarse yarns formed of comparatively short staple.

Another object of this invention is to so construct a knitting machine of this nature that the needle cylinder and skeleton cylinder can rotate in unison while the needle cylinder is adapted to be moved vertically relative to the skeleton cylinder and cam cylinder, to vary the length of the stitches.

Other objects of the invention will appear from the following description.

30 The invention consists in such novel features of construction and combination of parts as shall hereinafter be more fully described and pointed out in the claims.

Figure 1 represents a vertical sectional view of parts of a knitting machine illustrating this invention. Fig. 2 represents a sectional view taken on line 2—2 Fig. 1.

Similar characters of reference designate corresponding parts throughout.

40 In circular knitting machines having skeleton cylinders, so called, the yarn or thread has heretofore been supplied to the needles through the medium of a guide eye usually movable with the rotary cam cylinder around the needle cylinder. While this mechanism is operative and desirable under most conditions it is found that in the use of yarn of short staple or of unusual fineness, the movement of the yarn delivery device relative to the needles on which the yarn is engaged tends, at times, to exert undue strain on the yarn, which strain sometimes effects the stretching of the yarn or the breakage thereof. In the manufacture of goods from such

fine yarn or from yarn made of short staple fiber, it is desirable to avoid any undue strain on the yarn and this is accomplished, in large measure, by utilizing the rotary movement of the needle cylinder to bring the needles successively in position to engage the yarn and subsequently, in the rotation of the needle cylinder, to draw the yarn from its source of supply.

In carrying our invention into practice in a knitting machine having a skeleton cylinder, the problem is somewhat complicated by the necessity of rotating the skeleton cylinder in unison with the needle cylinder while, preferably, providing for the vertical movement of the needle cylinder independently of the skeleton cylinder at times to vary the length of the stitches and to this end we have produced the mechanism hereinafter described and claimed.

As shown in the drawings, in its preferred form, 5 indicates a main or base plate, of a knitting machine, open at its center and having the annular flange or way 6 and the circular wall 7 on which is fixed the usual cam cylinder 8 having the upwardly extending arm 9 having the yarn eye or guide 10 through which the yarn y is guided to a point where it is adapted to be engaged by the needles as will hereafter be explained. Depending from the base plate 5 is the member 11 having the flange 12 at its lower end, and the opening 13 through which extends the pin 14 of the usual hand operated needle cylinder lifting device 15. On the flange or member 12 is rotatably mounted the usual cam lifting-ring 16 of the well known automatic needle cylinder lifting mechanism which includes the cam ring 17.

Rotatably mounted within the wall 7 and having a bearing on the flange 6 is the annular bevel gear 18 which is driven from the bevel gear 19 of any suitable driving mechanism. The upper face of this gear 18 is preferably recessed to receive the base ring 20 of the skeleton cylinder having the series of flat vertical bars 21, 21 which form guides for the butts of the needles and afford side bearings for said butts to resist torsional strain exerted thereon by the cams of the cam cylinder. The ring 20 is secured to the gear 18 by screws whereby said ring and its guide bars 21, 21 rotate with said gear and rotary motion is transmitted from

said gear 18 to the needle cylinder 22 by means of the pin 23 which is fixed to said gear 18 and engages the vertical groove 24 in the outer surface of the needle cylinder 5 below the needle guide grooves 25, 25. In other respects than those noted, the needle cylinder 22 is similar to those heretofore constructed and is adapted to carry a series of needles *n* having the butts *b*. This needle cylinder is supported at its lower end by the cam ring 17 and is adapted to be lifted by the engagement of the pin 14 in its lifting movement or by or through the shifting of cam ring 16 so that during the rotation of said needle cylinder 22 said cylinder may be moved vertically to vary or adjust the length of the stitches. When, now the gear 18 is driven, the skeleton cylinder, formed by the ring 20 and the bars 21, 10 and the needle cylinder 22 are given a rotary movement in unison while the needle cylinder 22 is free to move vertically relative to the skeleton cylinder and to the cam cylinder 8. After the yarn *y* has been engaged with one or more of the needles, the continued rotative motion of the needle cylinder effects the drawing of the yarn through the guide eye 10 to a position in 15 which the hooks of the needles can engage the same.

We do not wish to limit ourselves to the exact means for slidably engaging the needle cylinder with the driving means as we are aware that this may be modified. We are also aware that the skeleton cylinder need not necessarily be engaged or connected with the driving mechanism exactly as shown.

Having thus described our invention, we

claim as new and desire to secure by Letters Patent—

1. A rotary knitting machine comprising a needle cylinder and a skeleton cylinder, both rotatably mounted, and rotary drive means for said cylinders having a member slidably engaged by said needle cylinder. 40

2. A rotary knitting machine comprising a skeleton cylinder rotatably mounted, a rotatable needle cylinder, means for moving said needle cylinder relative to the skeleton cylinder, and means for rotating said cylinders in unison. 45

3. A rotary knitting machine comprising a gear rotatably mounted in a horizontal position, a skeleton cylinder mounted on said gear, and a needle cylinder slidably mounted 55 and embraced by said skeleton cylinder.

4. A rotary knitting machine comprising a horizontal annular gear, a skeleton cylinder mounted on said gear, and a needle cylinder embraced by and driven through 60 said gear.

5. A rotary knitting machine comprising a horizontal base plate open at its center and having an annular bearing, a cam cylinder mounted on said plate, an annular gear journaled in said bearing, a skeleton cylinder fixed to said gear, and a needle cylinder embraced by said gear and slidably vertically, 65 said gear and said needle cylinder having complementary driving connection, substantially as described. 70
